(57) **CLAIM**

I claim the ornamental design for a food pan support, as shown and described.

DESCRIPTION

FIG. 1 shows a frontal perspective view of the food pan support.

FIG. 2 shows a front elevation view.

FIG. 3 shows a right side elevation view.

FIG. 4 shows a top plan view.

FIG. 5 shows a left side elevation view.

FIG. 6 shows a rear elevation view.

FIG. 7 shows a bottom plan view.

FIG. 8 is an end view thereof; and,

FIG. 9 is an end view in an alternate position.

The broken lines are for environmental purposes only and form no part of the claimed design.
